UNITED STATES PATENT OFFICE.

JAMES L. LEE, OF CHICAGO, ILLINOIS.

DESIGN FOR A FRAME FOR HAND CYLINDER PRINTING-PRESSES.

SPECIFICATION forming part of Design No. 26,467, dated December 29, 1896.

Application filed July 19, 1894. Serial No. 518,056. Term of patent 7 years.

To all whom it may concern:

Be it known that I, JAMES L. LEE, a citizen of the United States, residing at Chicago, in the county of Cook and State of Illinois, have 5 invented and produced a certain new and useful Design for Frames for Hand Cylinder Printing-Presses, of which the following is a full, clear, and exact specification, reference being had to the accompanying drawing, 10 forming a part thereof, and the said drawing being a perspective view of a hand cylinder printing-press frame embodying my design.

The leading features of my design consist of the frame portions A B, constituting the 15 sides and ends, respectively, and the portion G, projecting from the upper side of the frame and at one end thereof.

The frame A B is rectangular in general outline, and the portion A thereof consists of 20 a top member a and a bottom member a' , which members are connected together by upright portions a^2 , whose outlines are gradually rounded into the outlines of the horizontal members a a' , thus forming two openings, 25 having rounded corners when viewed from the side of the machine, and being bordered

by beads or ribs a^3 . The upright portions a^2 are apparently extended below the horizontal portion a' , as shown at a^4 , and these portions, as well as the under side of the horizontal portion a' , are bordered by beads or ribs a^5 .

The end portions B is the frame, apparently connecting the side portions A together, and they consist of a spider-like frame having a central opening surrounded by a bead b , the 35 frame portion surrounding such opening being substantially rectangular and having diverging arms or branches b^8 , which project against the inner sides of the frame portion A, the outer edge of the portion B being bordered by a bead or rib, as shown.

Having thus described my invention, what I claim as new, and desire to secure by Letters Patent, is—

The design for a hand cylinder printing- 45 press frame substantially as herein shown and described.

JAMES L. LEE.
